UNITED STATES PATENT OFFICE.

DAVID S. TINNIN, OF WASHINGTON, DISTRICT OF COLUMBIA.

CIGARETTE-HOLDER.

1,309,707.

Specification of Letters Patent. Patented July 15, 1919.

Application filed June 5, 1917. Serial No. 172,944.

To all whom it may concern:

Be it known that I, DAVID S. TINNIN, a citizen of the United States, residing at Washington, in the District of Columbia, 5 have invented certain new and useful Improvements in Cigarette-Holders, of which the following is a specification.

This invention relates to smokers' articles and more particularly to an improved cigarette holder which, while primarily designed for use by automobilists, possesses many features which render it as equally desirable for use by smokers in general.

Another aim of the invention is to so relatively position the finger ring proper and the cigarette receiving socket that when the ring is applied to a finger of either hand the cigarette will be positioned across the finger substantially in the same manner as when 10 directly held so that the cigarette is at all times in position for use and yet it is not necessary to grasp the same or the holder between two fingers.

A further object of the invention is to provide the ring with an ash tray supported in position beneath the lighted end of the cigarette so as to receive the ashes dropping therefrom.

In the accompanying drawings:

Figure 1 is a perspective view illustrating the manner of using the article embodying the present invention;

Fig. 2 is a view partly in side elevation and partly in vertical section through the article;

Fig. 3 is a front elevation of the article;

Fig. 4 is a perspective view thereof;

Fig. 5 is a view similar to Fig. 2 illustrating a slight modification of the invention;

Fig. 6 is a similar view illustrating a further modification of the invention;

Fig. 7 is a similar view illustrating that modification embodying the ash tray;

Fig. 8 is a perspective view illustrating the forward portion of the ash tray.

In its simplest form illustrated in Figs. 1 to 4, inclusive, the article comprises a finger ring 1, which may be made of metal or any suitable material and which is provided upon its upper side with an integral boss 2 having a cigarette receiving socket 3 which may be cylindrical or elliptical or, in fact, of any contour to receive a certain shape of cigarette. By reference to the said figures of the drawings it will be observed that the

axis of the socket is at right angles to the 55 axis of the finger opening of the ring so that when the ring is applied to a finger of either hand as, for example, the second joint of the middle finger of the left hand and a cigarette is inserted in the socket, the cigarette will 60 extend across the finger in substantially the same manner as when directly grasped. While the boss 2 is indicated in the drawings as integral with the ring it may be formed 65 separate therefrom and attached thereto in any suitable manner, and while the ring is 70 preferably broadened gradually in an upward direction to produce the boss, as clearly shown in Fig. 3, it will be understood that the ring and boss may have some other contour if desired. In order that the article may 75 serve also as a convenient match striker, the upper surface of the boss is roughened, as at 4, to provide a striking surface, the said upper surface of the boss being, furthermore, 80 transversely rounded so as not to present any sharp edges to the forefinger or any edges upon which a match head would be likely to be caught and torn from the stem. It will be understood, of course, that the ring will 85 be made in various sizes and that it may be ornamented in any desired manner.

In that form of the invention shown in Fig. 5 of the drawings the ring is provided in its lower side with a split 5 and is preferably made of malleable metal so that it may be spread or closed to increase or decrease its diameter thereby enabling the article to be placed upon the market in a single size. Also it is preferable in this form of the invention that the upper wall of the socket 3 be split longitudinally, as indicated by the 90 numeral 6, so that the size of the socket may be increased or decreased to accommodate different makes of cigarettes.

In that form of the invention shown in Fig. 6 of the drawings the boss supports a tubular cigarette holder 7 which is integral therewith and which in its general shape resembles the ordinary form of cigarette 100 holder. In this structure the mouth piece, of course, projects beyond one side of the boss and the body of the holder projects beyond the other side thereof.

In the form of the invention shown in Figs. 7 and 8 of the drawings the article 105 supports an ash receiving tray including a substantially trough-shaped shank 8 which

is integral with the ring at the base of the boss and extends forwardly therefrom, the concave upper side of the shank being designed to receive ashes dropping from the 5 cigarette. At its forward or outer end the said shank supports an ash receiving bowl 9 which is integral or rigid with the shank and within which is pivotally supported, as at 10, a supplemental bowl 11. The ashes 10 dropping in the bowl 11 may be discharged into the bowl 9 by merely tilting the bowl 11.

Having thus described the invention, what is claimed as new is:

In an article of the class described, a finger ring having a cigarette receiving socket, and 15 an ash receiving member extending from the ring and having a main receiving bowl and a pivoted bowl mounted therein and arranged to discharge thereinto.

In testimony whereof I affix my signature. 20

DAVID S. TINNIN. [L. s.]
